United States Patent Office.

SIMON INGERSOLL, OF BROOKLYN, NEW YORK.

Letters Patent No. 99,199, dated January 25, 1870.

IMPROVED FRICTION-CLUTCH.

The Schedule referred to in these Letters Patent and making part of the same.

To all whom it may concern:

Be it known that I, SIMON INGERSOLL, of Brooklyn, in the county of Kings, and State of New York, have invented certain new and useful Improvements in Friction-Clutches; and I do hereby declare that the following is a full, clear, and exact description thereof, reference being had to the accompanying drawings, and to the letters of reference marked thereon, which form a part of this specification, and in which—

Figure 1 represents a side elevation;
Figure 2, a plan view;
Figure 3, an inverted view;
Figure 4, a perspective of cam and lever;
Figure 5, a perspective view of the stock; and
Figure 6, a longitudinal section of my friction-clutch.
Similar letters of reference indicate like parts in all the figures.

The nature of my invention consists in the employment of a cam, and lever, constructed, arranged, and operating substantially in the manner and for the purpose hereinafter described.

To enable others skilled in the art to which my invention appertains, to make and use the same, I will now describe its construction and operation.

In the accompanying drawings—

A represents the stock or handle, provided with a cap or plate, b, at its upper end, said cap being formed with a groove or opening on its upper surface, as seen at a in fig. 2.

B represents the cam, consisting of a metal ring, formed with tooth c, on its inner circumference, and with projections f, f, on its outer circumference, to rest upon the cap b, for the diameter is not more than one-half that of the cap b.

D is a metal projecting plate, cast solid with the ring of the cam, and provided with two curved projec-

tions g, g', on its upper surface. These projections are arcs of different circles.

The outer projection, g, when the cam is in place, fits against the outer circumference of the cap b, as seen in fig. 1, and the inner projection, g', into the groove, seen at a in fig. 2, and the screw-end of the handle passes through the centre of the ring of the cam.

E is the lever, formed with a circular end and projection, e, to rest upon the ring of the cam.

The lever E has a hole through the circular end to receive the screw-end of the handle, and is also formed, at the same end, with two projections, p, p, which form arcs of the same circle.

The tooth c, on the cam, fits into the outer space, x, left between the two projections.

M is a spring, one end of which is inserted into the circular end of the lever, and the other end passed over a pin, n, secured to the cam.

The cam and lever are then inserted upon the cap b, the screw-end of the handle passing through the centre of each, and are retained in place by means of the nut p'.

Having thus described my invention,

What I claim as new, and desire to secure by Letters Patent, is—

The cam B, constructed as described, in combination with the lever E and cap or plate b, substantially in the manner and for the purpose described.

In testimony that I claim the foregoing as my own, I affix my signature, in presence of two witnesses.

SIMON INGERSOLL.
